CLAIM

The ornamental design for a clock, as shown and described.

DESCRIPTION

FIG. 1 is a perspective view of a clock showing our new design in a first transitional position.

FIG. 2 is a top view of the clock of FIG. 1.

FIG. 3 is a bottom view thereof.

FIG. 4 is a left view thereof.

FIG. 5 is a right view thereof.

FIG. 6 is a front view thereof in the first transitional position.

FIG. 7 is a front view thereof in a second transitional position.

FIG. 8 is a front view thereof in a third transitional position; and,

FIG. 9 is a rear view thereof.

The broken lines shown in the drawings are included for the purpose of illustrating environmental structure and form no part of the claimed design.

1 Claim, 5 Drawing Sheets
